CLAIM

I claim the ornamental design for a golf tee clip, as shown and described.

DESCRIPTION

FIG. 1 is a perspective view of a golf tee clip showing my new design;

FIG. 2 is a front elevation view thereof; the rear elevation view being the same as the front elevation view;

FIG. 3 is top plan view thereof;

FIG. 4 is a bottom plan view thereof;

FIG. 5 is a right side elevation view thereof; and,

FIG. 6 is a left side elevation view thereof.

The broken lines shown in FIG. 1 are included for the purpose of illustrating an associated golf tee that forms no part of the claimed design.

The appearance within the unshaded area of FIG. 3 forms no part of the claimed design.
